US00D983373S

(12) **United States Design Patent** (10) **Patent No.:** **US D983,373 S**
(45) **Date of Patent:** **** Apr. 11, 2023**

(54) **HUMERAL IMPLANT**

(71) Applicant: **Howmedica Osteonics Corp.**, Mahwah, NJ (US)

(72) Inventors: **Alexander Paul Wolfe**, Fort Wayne, IN (US); **David R. Stump**, Columbia City, IN (US)

(73) Assignee: **HOWMEDICA OSTEONICS CORP.**, Mahwah, NJ (US)

(**) Term: **15 Years**

(21) Appl. No.: **29/790,167**

(22) Filed: **Nov. 10, 2021**

Related U.S. Application Data

(62) Division of application No. 29/707,802, filed on Oct. 1, 2019, now Pat. No. Des. 938,590.

(51) **LOC (14) Cl.** **24-03**

(52) **U.S. Cl.**

USPC **D24/155**

(58) **Field of Classification Search**

USPC **D24/107, 155**

CPC **A61F 2/00; A61F 2/02; A61F 2/28; A61F 2/50**

(57)

CLAIM

The ornamental design for a humeral implant, as shown and described.

DESCRIPTION

FIG. 1 is a perspective view of a humeral implant of our design;

FIG. 2 is a right side view thereof;

FIG. 3 is a left side view thereof;

FIGS. 4-5 are front and rear views, respectively, thereof;

FIG. 6 is a top view thereof; and,

FIG. 7 is a bottom view thereof.

All features illustrated in broken lines form no part of the claimed design.

1 Claim, 6 Drawing Sheets
